UNITED STATES PATENT OFFICE.

JAMES J. MORRIS, OF CHICAGO, ILLINOIS, ASSIGNOR TO MILTON M. MAYER, OF CHICAGO, ILLINOIS.

DISPLAY APPARATUS.

Application filed June 14, 1926. Serial No. 115,700.

The present invention is related to display apparatus of the type illustrated, described and claimed in the pending application for Letters Patent of the United States filed by 5 Benjamin J. Buckingham February 28, 1924, Serial No. 695,648.

The object of the invention is to provide a display apparatus of the type mentioned, the general organization and construction 10 of which is such that the assembly of its parts may be effected with greater facility and ease than the construction referred to; it also aims to accomplish the operation of the apparatus in a more positive manner, 15 and with the expenditure of less power for such operation; and it also seeks to provide a construction which is more compact and less liable to derangement of the operative parts than the apparatus to which reference 20 has been made.

Other objects of the invention will appear as the nature of the improvements is better understood, the invention consisting substantially in the novel construction, combination and arrangement of parts as will be hereinafter fully described, illustrated in the accompanying drawings, and finally pointed out in the appended claims.

A preferred embodiment is disclosed here- 30 in. It is to be taken as such preferred embodiment, and is, therefore, illustrative of a practical adaptation of the inventive concept without imposing upon that concept undue restriction or limitations.

35 In the drawings,

Fig. 1 is a face elevation, partially in section, of a display apparatus constructed in accordance with the present invention;

Fig. 2 is an end elevation thereof, the en- 40 closing casing or housing being illustrated in section;

Figs. 3 and 4 are fragmentary vertical cross-sectional views on the lines 3-3 and 4-4, respectively, of Fig. 2;

45 Fig. 5 is a horizontal sectional view on the line 5-5, Fig. 1;

Fig. 6 is a fragmentary sectional view on the line 6-6, Fig. 5;

50 Figs. 7 and 8 are fragmentary sectional views, on an enlarged scale, on the lines 7-7 and 8-8, Fig. 1;

Fig. 9 is a cross-sectional view, on an enlarged scale of the power transmission between the motor and the driving shaft;

Fig. 10 is a cross-sectional view on the line 55 10-10, Fig. 9;

Fig. 11 is a top plan view, the casing being illustrated in section, of the structure disclosed in Figs. 9 and 10; and

Fig. 12 is a detail sectional view of the 60 auxiliary manually-operated drive.

Referring now in detail to the accompany- 65 ing drawings, the numeral 15 designates four corner posts which constitute the uprights of the machine frame. These corner posts 65 preferably are formed of angle iron. Connected to the lower ends of the posts 15 is a quadrangular base which includes end mem- 70 bers 16 and side members 17. These also are formed of angle iron, the end and side mem- 75 bers 16 and 17 being connected to afford sta- 80 bility to the base. A similar frame consti- 85 tutes the head of the machine, this also being formed of end rails 18 and side rails 19. These end and side rails also are connected, 75 and the entire head frame is mounted upon the upper ends of the corner posts 15.

The head frame affords a support for the driving mechanism of the machine. By ar- 85 ranging the driving mechanism on the head 90 frame this mechanism is at a remote point in the general structure but conveniently acces- 95 sible when such is desired, and its location at the top of the machine also affords a more uniform distribution of the power than if lo- 90 cated at the bottom thereof. The driving mechanism includes an electric motor 20 to the armature shaft of which is connected a speed reducing transmission 21. Included 100 in this transmission is a horizontally dis- 95 posed worm shaft 22, and interposed between this shaft and the armature shaft of the motor 20 is a coupling 23, electrically insulated from the motor.

The speed reducing transmission also in- 105 cludes a worm wheel 24 which meshes with the worm of the shaft 22. The wheel 24 is loosely mounted upon a driving shaft 25, and said shaft 25 is elongated so as to extend across the width of the machine, one of its extremities being mounted for rotation in a bearing bracket 26 which is sustained at one end of the head frame of the machine. The other end of the shaft 25 also projects beyond the casing of the speed reducing transmission, 110 and on each end of said shaft 25 there is mounted a fixed sprocket wheel 27 over which is trained a relatively short sprocket chain 28.

To lock the worm wheel 24 into engagement with the shaft 25, so as to cause the latter to rotate with said wheel, a detent 29 is arranged in a transverse slot 30 formed in said shaft 5 25. The detent 29 is mounted on a pivot pin 31 the ends of which are disposed in oppositely arranged longitudinal slots 32 formed in the shaft 25, and of such length as to permit the pivot pin 31 to have limited 10 movement in relation to said shaft. The ends of the pivot pin 31 also extend into a slidably collar 33 which surrounds the shaft 25, said collar 33 having an annular groove 34 into which fit a pair of inwardly extending 15 studs 35 carried by the forked end of an operating lever 36 pivotally mounted, as at 37, upon a supporting frame 38 which is carried by the head frame of the machine. The end of the detent 29 which is opposite to its 20 pivoted end is curved to provide an engaging nose 39. This nose is received by a slot 40 extending lengthwise of the bore of the hub of the wheel 24. A cam ring 41 is also fitted 25 within the bore of the hub of the wheel 24, the same being engaged by the nose 39 when the collar 33 is moved on the shaft 25 away from the casing of the speed reducing transmission. In that movement the nose 39 rides over the cam ring 41, against the pressure of a 30 spring 42, and in such movement the wheel 24 is released from its locked relation to the shaft 25. The spring 42 is disposed in the slot 30 of the shaft 35, and its pressure is exerted against the detent 29 to force the latter 35 into the slot 40 of the wheel 24. This follows when the collar 33 is moved towards the casing of the speed reducing transmission, after the nose 39 has cleared the cam ring 41 in that movement. Thus, provision is made for connecting and disconnecting the wheel 24 to the shaft 25. The purpose of this will appear 40 at a later point herein.

For actuating the lever 36 oppositely disposed cords or cables 43 are employed. One 45 of these cords or cables extends from each side of the lever 36, being threaded through a U-shaped guide 44 which is carried by the frame 38, the extremities of the cords or cables 43 extending through the casing of the machine 50 and to a point below the upper end thereof to be grasped conveniently by the attendant of the machine when it is desired to release or connect the wheel 24 from or to the shaft 25. It will be understood that the shaft 25 55 is the medium through which the power of the motor 20 is transmitted to the moving parts of the machine, and the operation of said shaft 25 is communicated through the sprocket chains 28 to such moving parts. The 60 latter include a plurality of display members on which the articles to be exhibited are mounted in a convenient way, and means for moving these display members in regular succession in a predetermined path with respect to the machine frame, thus successively 65

passing the display members by an observation point or points to exhibit the contents thereof to an observer or observers viewing the machine.

It has been stated that the present invention 70 contemplates such an organization of the structural elements of the machine as to render the same compact and operative under expenditure of relatively small power. To this end the organization of the machine, with 75 particular reference to the actuating parts for the display members, duplicates the actuating parts at opposite sides of the machine. It will be understood, therefore, that in the following description the structural features 80 enumerated therein are the same at either side of the machine, and because of this duplication there is a uniform distribution of the power from the motor 20, which renders the operation of the parts positive and steady, 85 and with freedom from jerks as the several display members pass throughout their path of movement.

Mounted on the uprights 15, at each side of the frame, and disposed in spaced relation 90 with respect to each other from the top to the bottom of the frame structure, is a plurality of supporting plates 45 of channel formation. Four of these plates are illustrated in the drawings. On certain of these plates 45 are 95 mounted guiding sprocket wheels 46. Two of these wheels 46 are located on each of the supporting plates 45 with which they are associated, and said wheels 46 are also arranged so that the axes of the upper wheels are in 100 vertical alignment with the axes of the lower wheels. By this arrangement the guiding sprocket wheels 46 are so aligned that a sprocket chain 47 which is trained thereover presents a quadrangular outline in its path 105 of movement, as clearly illustrated in Fig. 2. The side stretches, therefore, of the chains 47 move in a vertical path, while the top and bottom stretches move in a horizontal path.

Each of the sprocket wheels 46 is mounted 110 on a screw-threaded stud 48 by which the same is held for rotation on the supporting member 45 with which it is associated.

Fixedly connected to one of the guiding sprockets 46 at each side of the machine frame 115 at the top of the latter is a transmitting sprocket wheel 49, and it is to these sprocket wheels 49 that the chains 28 are connected, whereby motion is imparted from the shaft 25, through the sprocket wheels 27, to the 120 transmitting sprockets 49. This establishes driving connection from the shaft 25 to the chains 47, and on the operation of said shaft 25 the chains 47 are caused to move in the quadrangular path to which reference has 125 previously been made.

At a point between the upper and lower pairs of the main guiding sprocket wheels 46 is located a pair of transfer sprocket wheels 50. These wheels are supported by the plate 130

- 45 intermediate the plates on which the upper and lower main guiding sprocket wheels 46 are mounted. Each of the transfer wheels 50 is secured to the supporting member 45 by a 5 screw-threaded stud 51, and thus is capable of rotation in relation to said member 45. A transfer sprocket chain 52 is trained over the wheels 50, and said chain 52 also passes around an idler sprocket wheel 53 which is carried by 10 a depending supporting arm 54 having adjustable connection with the plate 45 to which the transfer sprockets 50 are connected. By the adjustment of the support 54 the tension of the transfer chain 52 may be regulated, it being tightened or loosened as desired in accordance with the adjustment of the support 54. Associated with one of the transfer wheels 50 is a guiding sprocket wheel 55 over which is trained a driving sprocket chain 56. 15
- 20 The latter also is trained over an auxiliary driving sprocket wheel 57 which is associated with one of the main guiding sprocket wheels 46 at the upper end of the machine. By the construction just described movement is communicated from the last mentioned main guiding sprocket wheel 46, actuated by the chain 47 which passes thereover, to the transfer chain 52, so that the chain 52 moves in unison with the chain 47.
- 25 30 Located at the lower end of each side of the machine frame is a further transfer sprocket chain 58. This is trained over a pair of transfer sprocket wheels 59 mounted by screw-threaded studs 60 on the supporting plate 45 at the lower end of each side of said frame. A supporting arm 61 carries an idler sprocket wheel 62 at its upper end, and said chain 58 passes over said sprocket wheel 62. The supports 61 are adjustably connected to their respective supporting members 45, and by the adjustment of said supports the tension of the chains 58 is either increased or decreased. 35
- 40 A guiding sprocket 63 is associated with one of the transfer wheels 59, and a driving sprocket chain 64 is trained over said wheel 63, and also over an auxiliary driving wheel 65 which is associated with one of the lower main guiding sprocket wheels 46. Thus the chain 64 communicates driving movement from the 45 sprocket chain 47 to the lower transfer chain 58, and this chain thereby also is caused to move in unison with the sprocket chain 47 and the upper transfer chain 52.
- 50 55 With the exception of the upper supporting member 45 the other supporting members are slotted, as at 66, and through said slots the fastening bolts, by which the members 45 are held in engagement with the frame members 15, are passed, thus providing for adjustment of the members 45, with resultant adjustment of the several sprocket wheels which are carried thereby, and this adjustment, in turn, may be utilized in the tensioning of the sprocket chains. 60
- 65 66 By referring to Fig. 5, the construction of the mounting of the several sprocket wheels on the frame of the machine will be seen. The construction shown in this view is typical of the construction of the several screw-threaded studs 48, 51 and 60. Each of the 70 studs is provided, adjacent to its outer end, with a flange 67, and mounted on the outer end is a fastening nut 68. This end of the stud passes through the body of the supporting member 45, and the nut 68 anchors the stud 75 in such rigid relation to the member 45 as to provide the required rigidity for the stud in order to insure a proper arbor for rotation of the wheels. Surrounding the stud is a sleeve 80 69. The hub of the wheel surrounds the sleeve 69, and the outer ends of the sleeves 69 bear against the flanges 67. Located at the inner ends of the studs, and fastened thereto as by headed screws 70, are a plurality of guard plates 71. These guard plates serve to screen 85 the sprocket chains and sprocket wheels, and prevent the display members from contacting with the wheels and chains. 90
- 95 As also illustrated in Fig. 5, it will be observed that as where one of the transfer sprocket wheels 50 and its associated driving sprocket 55 are mounted for conjoint rotation, the same are connected, as by screws 72. These screws pass through arcuate slots 72' formed in the wheel 50. When the screws are loosened the wheel 50 may be rotated to a limited extent with respect to the wheel 55, thus permitting relative adjustment between these wheels. The purpose of this will appear at a later point herein. 100
- 105 The display members are designated by the numeral 73. Each comprises a pair of side walls 74, and each of these side walls has a plurality of supporting flanges 75 extending inwardly therefrom, and formed in said sides by stamping out the metal of the sides. The flanges 75 afford means for sustaining trays 76 upon which to place the articles to be displayed, and said trays are secured to said flanges by machine screws 77 or their equivalent, which pass through openings formed in the flanges. 110
- 115 To suspend the display members 73, each is provided at its upper end with a transverse supporting sleeve 78. This sleeve extends between the side walls 74. A closure plug 79 is fitted in each end of the sleeve 78 and passes through the adjacent side wall 74, each of said plugs having a flange 80. The plugs are held in their respective ends of the sleeve 78 by frictional engagement therewith, the flanges 80 serving to limit the inward movement of the plugs as the same are driven into the sleeve. The outer ends of the plugs 79 project substantially beyond the side walls 74, and are bored out for the reception of pintles 81 carried by certain links of the chains 47, whereby the display members are caused to move with said chains as the latter are operated. An inwardly-extending bushing 120 125 130

82 adjustably receives one end of the sleeve 78, a screw 83 carried by the bushing serving to engage the sleeve and hold the latter within the bushing 82. When so adjusted the side walls 74 are held in a fixed relation with respect to each other.

For maintaining the display members 73 in proper vertical position, and to prevent the same swinging on the supporting member 78, 10 each side wall thereof has, at its outer face, a pair of guide rolls 84 and 85. These rolls are mounted on vertically disposed strips 86, arranged at the outer sides of the side walls 74. The rolls 85 are arranged at the lower 15 ends of the walls 74, while the rolls 84 are at a point substantially midway between the upper and lower ends of said side walls, being aligned with the rolls 85. During the travel of the chains 47, the rolls 84 and 85 travel 20 along the inner faces of the corner posts 15. The guard plates 71, as will be observed from Fig. 5, have their edges spaced from the flanges of the posts 15, and this spacing is 25 sufficient distance to provide for passage of the rolls 84 and 85 between the edges of said plates and the flanges of the corner posts. Thus, vertical grooves are formed in which the rolls 84 and 85 are adapted to travel as the display members 73 move along the vertical stretches of the chains 47. By reason 30 of this construction, the vertical position of the display members is preserved, and they are prevented also from swinging on the supporting members 78.

35 By reference to Figs. 2, 7 and 8, it will also be seen that the ends of the guard plates 71 are spaced apart a sufficient distance to provide horizontal guide spaces or passages for the rolls 84 and 85, and as the display members 73 follow the horizontal stretches of the chains 47 these rolls pass through said horizontal guide spaces. The distance between the latter is substantially the same as the distance between the rolls 84 and 85, and thus 40 said spaces readily accommodate said rolls as the display members 73 are transferred from one vertical stretch of the chains 47 to the other vertical stretch thereof. In this transfer, it will be understood that, in the movement of the chains 47, the display members 73 rise at one side of the machine and descend at the other. As the upper ends of the display members 73 reach the upper horizontal stretch of the chains 47, and pass around the 45 contiguous main guiding sprockets 46, it is necessary that the lower end of each of the display members 73 shall also be deflected in a horizontal direction, and thereby preserve the vertical position of the member in the 50 transfer from the ascending stretch of the chains 47 to the descending stretch thereof. To this end each side of each of the members 73 has a deflecting shoe 87 arranged at its lower end. This shoe has downwardly and 55 outwardly inclined edges 88, the lower end of

the shoes 87 being of sufficient width as to overlap the space between the flanges of the corner posts 15 and the edges of the guard plates 71. This assists in properly guiding the display members 73 as they rise and descend at the opposite sides of the machine. A contact finger 89 is carried by one of the flanges of each of the two corner posts 15 at one side of the machine. They project into the path of movement of the deflecting shoes 75 87. In the rise of these shoes the downwardly inclined edges 88 thereof which are in alignment with the contact fingers 89 strike the latter. These edges, in riding over the lower edges of the fingers 89, project the lower ends 80 of the uppermost display member 73 horizontally and into the space between the adjacent guard plates 71. This is the space which is also opposite to the horizontal stretch of the uppermost transfer chain 52. 85 The chain 52, at each side of the machine, is equipped with a pair of engaging studs 90, said studs being separated a distance approximately the diameter of the rolls 85. The movement of the chains 52 is timed, and the 90 studs 90 are positioned thereon at such points, that the rolls 85 will enter the space between the studs 90 as the lower end of the display member 73 which is being transferred begins its horizontal movement from the ascending 95 stretch of the chains 47 to the descending stretch thereof. When the studs 90 thus are engaged with the rolls 85 the movement of the transfer chains 52 effects movement of the lower ends of the display members 73 in unison with their upper ends, and because of this the vertical position of the members 73 is preserved. Thus the rolls 84 and 85 are caused simultaneously to enter the guide groove at the opposite side of the machine 100 formed by the flanges of the corner posts 15 thereat and the adjacent edges of the guard plates 71.

105 By the formation of the arcuate slots 72' in the wheel 50, and the adjustability thereby of 110 this wheel with respect to the wheel 55 when the screws 72 are loosened, the chains 52 may be moved to advance or retard the engagement of the studs 90 with respect to the rolls 85. This enables the proper timing of such engagement so that the lower ends of the display members will start the transverse travel across the machine at the same time that the upper ends of these members commence that travel.

115 The transfer chains 58 at the lower end of the machine act in a manner similar to the transfer chains 52, but there is associated with each of the lower chains 58, in proximity to the horizontal stretch thereof, a guide 120 flange 91. This guide flange parallels the horizontal stretch of the adjacent chain 58, its ends being curved with the axes of the wheels 59 as the center of the radius. In the descent, therefore, of the display members 125 130

73, the rolls 85 follow the guide flanges 91, and thereby are caused to deflect the lower ends of these members from the descending vertical path into the horizontal path of movement to transfer the members 73 from the descending stretch of the chains 47 to the ascending stretch thereof. The chains 58 are equipped with engaging studs similar to the studs 90 of the chains 52 in order to insure proper movement of the lower ends of the members 73, and the same provision also is made with the chains 58 and their wheels for timing engagement of the studs with the rolls of the members 73 as above described in connection with the chains 58.

That the horizontal stretches of the chains 47 may be relieved of the weight of the several display members 73, and the articles carried thereby, a supporting rail 92 is located in proximity to each of said stretches, as clearly seen in Figs. 3 and 4. The outer ends of the closure plugs 79 rest upon and travel over said rails 92, thereby imposing the weight of the members 73 on these rails, and preventing sagging of the chains 47. A smoother movement of the chains results. Each of said rails 92 also is arranged at the head of the adjacent guard plate 71 and the latter, therefore, is free from the weight of the members 73 as they are transferred from the ascending to the descending stretches of the chains, and vice versa.

The guard plates 71 are arranged between the corner posts 15 and are connected thereto by a plurality of anchoring brackets 93.

Because of the proximity of the chains 47 and 56, and to avoid rubbing contact of adjacent portions of these chains in the operation of the apparatus, it is desirable that such adjacent portion shall be properly separated. This is accomplished by vertically disposed division strips 94, preferably formed of relatively thin sheet metal, said strips being mounted on the adjacent stanchions 95 one of which is located within each of the corner posts 15. In thus separating the chains referred to their frictional engagement is prevented so that the life of the chains is prolonged.

In the display of the merchandise or other articles to be exhibited by the members 73, it will be understood that any number of trays 76, such as may be accommodated by the supporting flanges 75 of the side walls 74, may be employed. The articles are placed on the trays, and the latter separated a sufficient distance determined by the height of the articles thereon. In some instances it is desirable that the articles be placed in various angular positions, or at inclinations to the trays 76. To permit this one or more supporting bars 96 may be utilized, each of said bars having at its ends depending studs designed to engage the openings of the flanges 75, and thus permit the bars to be detachably

connected to said flanges. These bars extend across the entire width of the display members 73, and are arranged at such height above the trays 76 as to provide the requisite support for the articles in the inclined or angular position in which the articles may be placed for their most effectual display. Furthermore, the bars 96 afford means from which articles may be suspended, if it be desired to dispense with the trays 76, or the latter and the bars may be employed jointly, certain articles being placed on the trays, and others being suspended from the bars. Thus, the range of the apparatus for the purposes for which it is designed may be considerably extended.

In Fig. 12 is illustrated in enlarged detail the auxiliary manually-operated drive for the machine. When the motor 20 is disconnected from driving relation with the chains 47, as when the detent 29 has been shifted to disconnect the wheel 24 from the driving shaft 25, it is essential that provision be made for movement of the chains 47 for shifting the position of the display members 73. In such condition the manual drive illustrated in Fig. 12 is employed. This includes a shaft 97 on one end of which is mounted a worm 98. The latter is designed to engage a worm wheel 99, which wheel is associated with one of the main guiding sprockets 46. The shaft 97 is fitted within a sleeve 100 pivotally mounted to one of the corner posts 15, as at 101. This pivotal mounting permits the swinging of the shaft 97 so that the worm 98 may be brought into engagement with the wheel 99 or released from such engagement. The shaft 97 is of sufficient length to project beyond the casing or housing of the machine. Its outer extremity is squared, or otherwise suitably shaped, for the application of an operating crank. Such extremity also passes through an adjustment plate 102 having a slot and bolt connection 103, whereby the plate 102 may be moved in either direction of its length, whereupon the worm 98 may be engaged with or released from the worm wheel 99. When so engaged, it is evident that rotation of the shaft 97 will operate the chains 47 to move the display members 73 to any desired point, and if the motor 20 be disconnected from its driving relation to the shaft 25, the manual drive which has just been described may be employed for the actuation of the machine.

The framework of the machine, and the moving parts thereof, may be enclosed in a casing or housing 104, and when so enclosed these parts are obscured from view. A suitable portion of the casing may remain open so that each of the display members 73 may pass successively into view. In such circumstances a central partition 105 is arranged between the vertical stretches of the chains 47 to serve as a screen between the member 73 which is passing the observation opening,

and the member which is immediately in rear thereof. This adds to the attractiveness of the machine and permits observation only of that member 73 which is immediately before the observation opening.

From the foregoing description the utility and operation of the invention will be readily understood. Suitable controlling connections for the motor 20, such as the requisite switch mechanism and electrical wiring, obviously are to be included, but such controlling mechanism forms no part of the present invention. When the motor is energized the driving shaft 25 is operated and transmits its motion through the chains 28 to the chains 47. This causes the several display members 73 to move upwardly and downwardly at opposite sides of the machine, and successively to pass a given point for observation. Articles of merchandise, or such other articles which it is desired to be displayed, may be placed on the several members 73, and thus will be exhibited in the movement of the members 73. Each of these members follows the quadrangular path in which the chains 47 are arranged, and thus alternately rise and descend at the opposite vertical stretches of these chains. In transfer from one side of the machine to the other the members 73 are preserved in their vertical suspended positions, so that the articles carried thereby are not disturbed, and from the fact that the lower ends of the members 73 are guided in unison with the upper ends thereof as the members are transferred from one vertical stretch of the chains 47 to the other vertical stretch of the same, the members 73 move with freedom and are not subjected to jerks or other uncertain movements.

40 I claim:

1. In a display apparatus of the character described, the combination with a frame, of a pair of endless chain display conveyors arranged at opposite sides of said frame, guide wheels over which said conveyors are trained and arranged to support the conveyors for travel in a quadrangular path, driving mechanism for said conveyors, and independent endless chain transfer conveyors also associated with said endless conveyors for effecting transfer from one stretch of the endless conveyors to the other of the articles to be displayed.

2. In a display apparatus of the character described, the combination with a frame, of a pair of endless chain display conveyors arranged at opposite sides of said frame, guide wheels over which said conveyors are trained and arranged to support the conveyors for travel in a quadrangular path, driving mechanism for said conveyors, means for supporting on said conveyors the articles to be displayed, said endless conveyors being mounted so that opposite stretches thereof travel in vertical paths, and independent end-

less chain transfer conveyors associated with said endless display conveyors for effecting transfer from one stretch of the endless display conveyors to the other stretch thereof of the supporting means for the articles to be displayed, said transfer conveyors being located at different points with reference to the endless conveyors, whereby to transfer the supporting means for the articles to be displayed at both the upper and lower portions 75 of the apparatus.

3. In a display apparatus of the character described, the combination with a frame, of a pair of endless chain display conveyors arranged at opposite sides of said frame, guide 80 wheels over which said conveyors are trained and arranged to support the conveyors for travel in a quadrangular path, driving mechanism for said conveyors, means for supporting on said conveyors the articles to be displayed, said endless display conveyors being mounted so that opposite stretches thereof travel in vertical paths, separate endless chain transfer conveyors associated with said endless display conveyors for effecting transfer 90 from one stretch of the endless display conveyors to the other stretch thereof of the supporting means for the articles to be displayed, and driving connections between the endless conveyors and the transfer conveyors for actuating the latter in unison with the endless conveyors.

4. In a device of the character described, a supporting frame, an endless chain main conveyor of quadrangular form, a plurality of 100 auxiliary chain conveyors transversely arranged with respect to the main conveyor, article carriers on the main conveyor, guard plates between the article carriers and the conveyor chains defining guideways for portions of the carriers, means for driving the main conveyor, and chain and sprocket connections between the main conveyor and the auxiliary transverse conveyor.

5. In a display apparatus of the character 110 described, a supporting frame, an endless chain main conveyor, a plurality of auxiliary transfer endless chain conveyors transversely arranged with respect to the main conveyor, article carriers supported in parallel position 115 on the main conveyor, sprocket and chain connections between the main and auxiliary conveyors, said connections being adjustable to permit timing of the auxiliary conveyor relative to the main conveyor, means for deflecting the article carriers into positive engagement with the auxiliary conveyors, said auxiliary conveyors effecting the transfer of the article carriers from one reach of the main conveyor to the other.

6. In a display apparatus of the character described, a supporting frame, a pair of main endless conveyor chains arranged at opposite sides of said frame, guide wheels over which the conveyor chains are trained supporting 130

the conveyors for travel in a quadrangular path, a plurality of auxiliary endless chain conveyors on opposite sides of said frame arranged transversely of the main conveyor, 5 chain and sprocket connections between the main and auxiliary conveyors, means for driving the conveyors, a plurality of guard plates mounted in spaced relation with the frame and each other defining guideways between the plates, article carriers supported on the main conveyor having guide members which traverse the guideways, said auxiliary conveyors being adapted to engage and transfer the article carriers from one reach of the 10 main conveyor to the other, and deflecting means for positively moving the carriers into engagement with the auxiliary chain conveyor.

7. In a display apparatus of the character 20 described, a supporting frame, a pair of main endless conveyor chains arranged at opposite sides of the frame, guide wheels over which the conveyor chains are trained supporting the conveyor chains for travel in a quadrangular path, a plurality of auxiliary endless 25 chain conveyors on opposite sides of the frame arranged transversely of the main conveyor, chain and sprocket connections between the main and auxiliary conveyors, means for driving the conveyors, a plurality of guard plates mounted in spaced relation with the frame and each other defining guideways between the plates and portions of the frame, article carriers supported on the main 30 conveyor having guide members which traverse said guideways, said guard plates being provided with supporting rails for engagement with the guide members of the article carriers to relieve the weight of the carriers 35 on the transverse reach of the main conveyor 40 chains.

8. In a display device comprising a supporting frame with endless chain main conveyors arranged on opposite sides of the 45 frame providing storage and display space therebetween, a plurality of auxiliary chain transfer conveyors transversely arranged with respect to the main conveyors, article carriers supported at their upper ends from the chains of the main conveyor and having means for engagement by the transverse conveyor to insure positive transfer of the lower ends of the carriers from one reach of the main conveyor to the other.

55 9. In a display device, a frame structure consisting of a plurality of vertically disposed angle upright members connected at their base and heads by quadrangular frame structures, spaced horizontal channel support members connecting the upright members on opposite sides of the frame, stud shafts mounted in alinement on the channel supports, guide sprockets mounted on the shafts, endless chains trained around certain of the 60 sprockets to travel in a quadrangular path

constituting a main article conveyor, separate chains trained around remaining sprockets and constituting a conveyor transverse to the main conveyor, driving means mounted on the head of the frame, and chain connections between the driving means and the separate conveyors. 70

10. In a display conveyor, a frame structure consisting of a plurality of upright members connected at their base and heads by quadrangular frame structures, driving means consisting of a motor and transmission mounted on the frame, endless chain display conveyors mounted on opposite sides 75 of the frame, a plurality of transverse endless chain conveyors mounted on opposite sides of the frame, chain and sprocket connections between the driving means and the display conveyors, and sprocket and chain connections between the display and transverse conveyors, the connection between the display and transverse conveyors comprising 80 cooperating sprockets adjustably connected to permit timing of the transverse conveyor with respect to the main conveyor. 85

11. In display apparatus of the character described, a supporting frame, two endless conveyor chains on opposite sides of said frame, four wheels supporting and guiding each chain over a quadrangular path having two substantially vertical stretches and two connecting transverse stretches, article carriers disposed in the space between said chains supported thereon, the weight of said carriers being carried by said chains in the 95 said vertical stretches, and transverse rails on said frame on which the weight of said carriers is supported during the movement over the transverse stretches. 100

12. In display apparatus of the character described, a supporting frame, two endless conveyor chains on opposite sides of said frame, four wheels supporting and guiding each chain over a quadrangular path having two substantially vertical stretches and two connecting transverse stretches, a vertically 105 extending carrier disposed in the spaces between said chains and having its upper ends supported on said chains to be guided along said quadrangular path, and a rail guide defining a quadrangular path similar to the quadrangular path of said chains for guiding the lower portion of said carriers. 110

13. In display apparatus of the character described, a supporting frame, two main endless conveyor chains on opposite sides of said frame, four wheels supporting and guiding each chain over a quadrangular path having two substantially vertical stretches and two connecting transverse stretches, a vertically 115 extending carrier disposed in the spaces between said chains and having its upper ends supported on said chains to be guided along said quadrangular path, a rail guide defining a quadrangular path similar to the quadrangular path of said chains for guiding the lower portion of said carriers. 120

angular path of said chains for guiding the lower portion of said carriers, and a second set of conveyor chains for positively moving the lower portion of said carrier over portions of said rail guide.

14. In display apparatus of the character described, a supporting frame, two main endless conveyor chains on opposite sides of said frame, four wheels supporting and guiding each chain over a quadrangular path having two substantially vertical stretches and two connecting transverse stretches, a vertically extending carrier disposed in the space between said chains and having its upper ends supported on said chains to be guided along said quadrangular path, a rail guide defining a quadrangular path similar to the quadrangular path of said chains for guiding the lower portion of said carrier, a second set of conveyor chains for positively moving the lower portion of said carrier over portions of said rail guide, and a positive driving connection between said main conveyor chains and said second set of conveyor chains to cause synchronous movement of the upper and lower portions of said carriers over said similar paths.

15. In display apparatus of the character described, a supporting frame, two main endless conveyor chains on opposite sides of said frame, four wheels supporting and guiding each chain over a quadrangular path having two substantially vertical stretches and two connecting transverse stretches, a vertically extending carrier disposed in the spaces between said chains and having its upper ends supported on said chains to be guided along said quadrangular path, a rail guide defining a quadrangular path similar to the quadrangular path of said chains for guiding the lower portion of said carriers, a second set of conveyor chains for positively moving the lower portion of said carrier over portions of said rail guide, and a positive driving connection between said main conveyor chains and said second set of conveyor chains to cause synchronous movement of the upper and lower portions of said carriers over similar path, said driving connection being adjustable to permit adjustment of the phases of movement of the main conveyor chains and said second sets of conveyor chains for controlling the relative positions of the upper and lower portions of said carrier during said movement.

16. In a display device of the character described, a supporting structure comprising two spaced parallel side frames, cross members interconnecting said side frames and holding the same in spaced relationship, two endless main sprocket chains, four sprocket wheels rotatably supported on each of said side frames for training thereon said chains to define a quadrangular path, a carrier disposed in the space between said chains and

having its upper portion supported thereon whereby the upper portion of said carrier will be moved with said chains over the quadrangular path thereof, and a second set of endless sprocket chains for positively moving the lower portion of said carrier over a quadrangular path parallelly displaced against the path of said main sprocket chains.

17. In a display device of the character described, a supporting structure comprising two spaced parallel side frames, cross members interconnecting said side frames and holding the same in spaced relationship, two endless main sprocket chains, four sprocket wheels rotatably supported on each of said side frames for training thereon said chains to define a quadrangular path, a carrier disposed in the space between said chains and having its upper portion supported thereon whereby the upper portion of said carrier will be moved with said chains over the quadrangular path thereof, and a second set of endless sprocket chains for positively moving the lower portion of said carrier over a quadrangular path parallelly displaced against the path of said main sprocket chains, said second set of sprocket chains being supported by said side frames coplanar with corresponding main chains.

18. In a display device of the character described, a supporting structure comprising two spaced parallel side frames, cross members interconnecting said side frames and holding the same in spaced relationship, two endless main sprocket chains, four sprocket wheels rotatably supported on each of said side frames for training thereon said chains to define a quadrangular path, a carrier disposed in the space between said chains and having its upper portion supported thereon whereby the upper portion of said carrier will be moved with said chains over the quadrangular path thereof, two additional endless sprocket chains operably mounted on each side frame in spaced relationship below the upper and lower transverse stretches of the corresponding main chain, and means on the lower portions of said carrier arranged to be engaged by said additional sprocket chains for positively transferring the lower portion of said carrier from one vertical stretch to the other while the upper portion thereof is being transferred by said main chains.

19. In a display device of the character described, a supporting structure comprising two spaced parallel side frames, cross members interconnecting said side frames and holding the same in spaced relationship, two endless main sprocket chains, four sprocket wheels rotatably supported on each of said side frames for training thereon said chains to define a quadrangular path, a carrier disposed in the space between said chains and

having its upper portion supported thereon whereby the upper portion of said carrier will be moved with said chains over the quadrangular path thereof, and guard plates 5 supported by each side frame in front of said sprocket chains, the shape of said guard plates being such that the edges thereof constitute guide rails defining quadrangular paths similar to and parallelly displaced 10 against the path of said main chains, the lower portion of said carrier having roller means engaging said guide rails for movement over the quadrangular path thereof, said additional sprocket chains being arranged 15 to engage said roller means for positive movement thereof over the horizontal transverse portions of said guide rails.

20. In a display apparatus, a frame structure including two spaced upright side frames, each side frame comprising two up- 20 standing posts and four transverse members holding said posts in spaced relationship, a pair of main sprocket wheels rotatably supported on the uppermost transverse member, 25 a second pair of main sprocket wheels disposed on the transverse member third from the top, the sprocket wheels on each of said transverse members being horizontally spaced from each other, an endless sprocket 30 chain trained over said four sprocket wheels, a third pair of sprocket wheels on the trans- 30 verse member second from the top, a fourth pair of sprocket wheels on the transverse member fourth from the top, an independ- 35 ent endless sprocket chain trained over the

third pair of sprocket wheels, a second independent endless sprocket chain trained over the fourth pair of sprocket wheels, an idler sprocket wheel supported by said second transverse member for tensioning the first 40 independent sprocket chain, an adjustable arm holding said idler on said transverse member, a similar idler supporting arm associated with the fourth transverse member for tensioning the second independent sprocket 45 chain, said first independent sprocket chain being coplanar with said main chain and being disposed in the space therebetween, said second independent sprocket chain being co- 50 planar with the first independent sprocket chain, a sprocket chain connection between one of the sprocket wheels on the uppermost transverse member and one of the sprocket 55 wheels on the second transverse member, a sprocket chain connection between one of the sprocket wheels on the third transverse member and one of the sprocket chains of the fourth transverse member whereby the two independent sprocket chains are driven in 60 synchronism with the main sprocket chain, and carriers disposed in the space between said two main sprocket chains and having the upper ends thereof supported and guided by said main sprocket chains, the lower portion of said carriers being arranged to engage and be guided by said independent 65 sprocket chains.

In testimony whereof I have hereunto subscribed my name.

JAMES J. MORRIS.
